UNITED STATES PATENT OFFICE.

THOMAS E. HEETER, OF ST. LOUIS, MISSOURI.

BOOKMAKING MACHINE.

Application filed November 20, 1920. Serial No. 425,346.

To all whom it may concern:

Be it known that I, THOMAS E. HEETER, a citizen of the United States of America, and a resident of the city of St. Louis and State 5 of Missouri, have invented certain new and useful Improvements in Bookmaking Machines, of which the following is a specification.

The primary object of this invention is to 10 provide an improved arrangement of parts for applying the glued facing to the backs of books.

Another object of the invention is to provide improved means for feeding the facing 15 material to the book facing applying mechanism.

A further object of the invention is in providing an improved book feeding mechanism for feeding the book singly from the 20 magazine to the facing mechanism.

A still further object of the invention is in providing an improved arrangement of gripping means for engaging and drawing 25 the facing material.

Other and further objects will appear in the specification and be specifically pointed 30 out in the appended claims, reference being had to the accompanying drawings exemplifying the invention, and in which,

Figure 1 is a plan view of this improved machine.

Figure 2 is a side elevation of the upper portion of the machine.

Figure 3 is a right hand end view of Figs. 35 1 and 2.

Figure 4 is a vertical cross section taken approximately on the line IV—IV of Fig. 2.

Figure 5 is a longitudinal section taken approximately on the line V—V of Fig. 1.

Figure 6 is an enlarged fragmentary cross section taken approximately on the line VI—VI of Fig. 5.

Figure 7 is an enlarged sectional detail view of one of the grippers, showing the 45 adjustable gripping plate.

Figure 8 is a detail view of a portion of the throw arm and co-operable cam.

With reference to the drawings, a feed table 1 is horizontally extended from one of the end members 2 of this improved machine, said table 1 being supported between the side frames 3, and extending from said frames 3 is a swinging frame 4 bearing a guiding roller 5, and arranged between the

extending end of said frames 3 is another 55 guiding roller 6, said rollers 5 and 6 adapted to guide the facing or binding material 7 to the feed table 1.

Horizontally supported by the frame 3 is a rock shaft 8, and rigidly secured to said rock shaft are a pair of spaced apart, upwardly extending arms 9, and supported between the upper ends of said arms is a cutting knife 10, said knife adapted to co-operate with a stationarily held knife 11, which is horizontally supported by the end member 2. Secured to one end of the rock shaft 8 is an operating arm 12, the extending end 13 of said arm being held against an operating cam 14 by the coil spring 15. 70

Oppositely disposed from the end member 2 is an end member 16, and extending longitudinally between said members 2 and 16 and on a horizontal plane with the feed table 1 is a pair of spaced apart guiding members 17, and paralleling said members 17 on each side thereof, and supported by the end members 2 and 16 is a horizontally arranged trackway 18. Arranged above and paralleling one of the guiding members 17 is a feed roller 19, one end of said roller being supported by an adjustable arm 20 which is secured to the end member 2, whereas the opposite end of said roller is supported by an adjustable arm 21, which is 80 borne by the end member 16, and secured to said roller adjacent the arm 21 is a pinion 22, said pinion being in mesh with a pinion 23 which is secured to one end of a feed roller 24, said roller 24 being arranged above the other guiding member 17 and held in spaced apart opposing position from the roller 19 by bearings which are respectively provided in the end members 2 and 16. 85

Arranged in vertical alinement with the feed roller 19 beneath one of the guiding members 17, is a squeezing roller 25, the ends of said roller being supported by adjustable arms such as 26 that are respectively supported from the end members 2 and 16, and secured to the end of said roller 25 adjacent the end member 16, is a pinion 27 meshing with a pinion 28, said pinion 28 being carried by an oppositely disposed squeezing roller 29 which is held spaced apart from the roller 25 by bearings respectively provided by the end members 2 and 16. 90

Arranged in vertical alinement with the feed roller 19 beneath one of the guiding members 17, is a squeezing roller 25, the ends of said roller being supported by adjustable arms such as 26 that are respectively supported from the end members 2 and 16, and secured to the end of said roller 25 adjacent the end member 16, is a pinion 27 meshing with a pinion 28, said pinion 28 being carried by an oppositely disposed squeezing roller 29 which is held spaced apart from the roller 25 by bearings respectively provided by the end members 2 and 16. 95

Carried by the squeezing roller 29 adjacent the pinion 28 is a sprocket 30, and mounted over said sprocket is an endless link belt 31, said link belt meshing with a driving sprocket 32 which is mounted on a stub shaft 33, said stub shaft extending from the end member 16, and borne by said stub shaft is another sprocket 34 around which a link belt 35 passes, said link belt also engaging a driving sprocket 36 which is carried by the cam shaft 37, said cam shaft being horizontally supported between the end members 2 and 16, and mounted on said shaft 37 is a bevelled gear 38 meshing with a matching gear 39 which is mounted on a stub shaft 40, said shaft being supported by the bracket 41 which is extended from the end member 2, and carried by said stub shaft 40 is a sprocket 42, said sprocket receiving motion from the endless belt 43 which passes over a sprocket 44 carried by the driving shaft 45, said shaft 45 being driven from the reduction gearing 46 which receives motion from a motor not shown.

Supported between the end members 2 and 16 is a horizontal rock shaft 47, and rigidly secured to said shaft and extending upwardly therefrom are a pair of pusher arms 48, and secured to the upper end of each of said arms and extending inwardly therefrom is a curved plate 49, each bearing a cleat 50 on its upper surface, each of said plates 49 adapted to underengage a book-receiving magazine 51 which is comprised of the upstanding members 52 and 53 as well as a plurality of under engaging members 54.

Secured to the shaft 47 between the pusher arms 48 is a rock lever 55, and extending upwardly from one end of said lever are a pair of coil springs 56, said springs at their upper ends being secured to a tie cross member 57 which is arranged between the upper ends of the end members 2 and 16, the opposite end of said lever 55 bearing a roller 58, said roller being held against the cam 59 which is carried by the cam shaft 37.

Arranged between the end members 2 and 16 above the feed roller 19 is a deflecting member 60, and oppositely disposed from said member and located above the feed roller 24 is another deflecting member 61, said members 60 and 61 serving to receive and guide the books as they are singly discharged from the magazine 51. Carried by the guiding member 61 is an adjustable stop 62, and secured to the end member 2 is a bracket 63 supporting a turnable member 64, one end 65 of said member adapted to be engaged by the set screw 66 which is borne by one of the pusher arms 48, the other end 67 of said member extending to a position above the feed rollers 19 and 24, and the one side of the deflecting member 60.

From an inspection of Figs. 4 and 6 it is

to be noted that each of the trackways 18 is arranged a distance away from a respective guiding member 17, thereby providing longitudinal ways such as 68, and arranged to travel within each of said ways is a gripper 69, each gripper being comprised of a stationarily held lower jaw 70 which is secured to the underside of a horizontally arranged plate 71 and an upper movable jaw 72, each of said upper jaws being rigidly secured to a rockable bar 73 which extends horizontally beneath the feed rollers 19 and 24, said bar being supported in bearings 74, a pair of which is provided on each of the lower jaws 70. This bar 73 extends to one side of the feed roller 19, the extending end thereof being supported in a bracket 75 which forms part of the plate 71, the upper end of said bracket having a bearing portion 76 which is rigidly secured to a sliding guiding bar 77, and depending from the plate 71 is a portion 78 which is secured to a link belt 79. Passing through the bar 73 is a rocking pin 80, and carried by the upper end of said pin is a roller 81 which underengages a leaf spring 82 which extends from the portion 76 of the plate 71, said pin adapted to abut a projection 83 which is extended from the end member 16 as well as abut a projection 84 which extends from the end member 2.

The link belt 79 passes around a pair of sprockets 85 and 86, the sprocket 86 being mounted on a shaft 87 which is horizontally supported by the side frames 3, and mounted on the opposite end of said shaft is a sprocket 88 which is engaged by a chain length 89, one end of said chain being secured at 90 to said sprocket 88, the depending end of said chain bearing a weight 91. The sprocket 85 is mounted on a horizontally arranged shaft 92 which is supported by brackets 93 from the end member 16, and mounted on the opposite end of said shaft 92 is a gear 94, and in mesh therewith is a rack bar 95, having one end pivotally secured at 96 to a throw arm 97, said arm being intermediately pivoted at 98 to the tie rod 99.

Carried by the lower end of the throw arm 97 is a roller 100, and co-operable with said roller is a cam 101, which is mounted on the driving shaft 45.

Mounted on one end of the cam shaft 37 is a cam 102, which bears against a roller 103 carried by a lever 104 which is pivoted at 105 to the end member 16, and swingingly secured to the upper extending end of said lever is a rack bar 106, the teeth of which are held in mesh with the pinion 23 by the guiding roller 107.

In the operation of this improved machine, the binding material 7 is led to the feed table 1 after passing through the glue pot not shown, which glues the upper face

of the material and upon motion being imparted to the machine through the reduction gearing 46, the grippers 69 when in a receptive position to engage the forward end of the glue faced material 7 are in a position beneath the knife 10, and in which all of the active parts of the machine are in the positions as disclosed in Figs. 1 to 4 when the grippers are in the position mentioned.

10 In the just mentioned position of the parts from an inspection of Fig. 2, it is to be noted that the weight 91 is in an elevated position, and on account of the cam 101 being in a position wherein it is inactive on the throw arm 97, said weight will cause the shaft 87 to be turned in a right hand direction as it is lowered by gravity, thereby causing the upper strand of the chain 79 to travel towards the end member 16, and inasmuch as the plate 71 which carries the grippers 69 is connected to the upper strand of said chain 79 by the portion 78, said grippers will be moved rearwardly thereby drawing the sheet of binding material 7 rearwardly or 25 towards the end member 16.

Preparatory to operating the machine, the magazine 51 is loaded with books that are to be faced as shown in Fig. 4, and in this disclosure such books are relatively thin, and 30 intended for bank pass books, and in which the length thereof is about seventeen inches, and after each book has passed through this improved machine, each length is cut transversely into three parts.

35 After the grippers 69 have travelled an approximate distance of seventeen inches rearwardly from the end member 2 said grippers are stopped in their rearward travel, such stopping being created by the dwelling portion 108 of the cam 101 bearing against the roller 100 of the throw arm 97, in which said throw arm is held in a locking position against the moving force created by the descending weight 91, said throw arm through the rack bar 95, which is connected thereto, and to the gear 94, thereby preventing the link belt 79 from moving.

Simultaneously with the stopping of the 50 grippers 69 the cam 14 of the cam shaft 37 became ineffective on the operating arm 12 of the rock shaft 8 towards holding said arm elevated, thereby allowing the spring 15 to act on said rock shaft 8, in which the arms 9 bearing the knife 10 is allowed to descend and sever the binding material, thereby leaving approximately seventeen inches of material, which is further designated as A, held by the grippers.

60 After the material has been severed, the roller 100 of the throw arm 97 is allowed to traverse the descending face 109 of the cam 101, in which the weight 91 will become further effective towards again moving the grippers 69 a further distance rear-

wardly until the roller 100 of the throw arm 97 is engaged by the dwelling portion 110 of the cam 101, which second position of stopping of the grippers 69 is the end of their rearward travel.

Just prior to the grippers 69 reaching the end of their rearward travel, the lower end of the rocking pin 80, which is borne by the rock bar 73 of the grippers, was engaged by the projection 83 which is extended from the end members 16, thereby causing said pin 80 to rock the bar 73 and swing the upper jaws 72 upwardly out of gripping position with the severed strip of binding material A.

On or about the time the knife 10 is severing the material strip A, the serrated portions 111 of the cam 59 become effective on the rock lever 55 of the pusher bars 48, in which the roller bearing end of said lever 55 is caused to be moved intermittently upward and the curved plate 49 of each of said pusher arms 48 are moved back and forth beneath the lowermost book B, and in which the cleat 50 of each plate 49 will engage the front edge of said book B, thereby pushing said book a distance from beneath the next book thereabove, and as the grippers 69 reach the end of their travel, the grooved portion 112 of the cam 59 will allow the springs 56 to become effective towards moving the plates 49 of the pusher arms 48 inwardly their full distance so that the cleats 50 will discharge the book B from the magazine 51, in which the forward portion of the discharged book will engage the deflecting member 60 thereby directing the book onto and between the upper arranged rollers 19 and 24.

Simultaneously with the discharging of the book B to a position above and between said rollers 19 and 24, the cam 102 of the cam shaft 37 becomes effective on the roller 103 of the lever 104, thereby moving said lever and the rack bar 106 pivoted thereto, and causing the pinion 23 of the roller 24 and the pinion 22 of the roller 19, with which said pinion 23 is in mesh, to revolve, thereby feeding the book B between said rollers 19 and 24, and inasmuch as the strip of glued material A has been arranged upon the guiding members 17, and trackways 18 by the grippers 69 to an alining position beneath the descending book B, the hinged portion of said book will engage the glued strip of material A at its approximate longitudinal center, thereby forcing the hinged portion of the book and the material engaged thereover through the longitudinal space or slot 113 provided between the guiding members 17. Inasmuch as the squeezing rollers 25 and 29 are continuously moving on account of the sprocket and chain arrangement thereto, and the meshing pinions 27 and 28, the continual feeding of the roll-

ers 19 and 24 upon the book B will force said book and the glued material A between said squeezing rollers 25 and 29, said rollers firmly pressing the glued surface of the binding material A against the back of the book B, and as the book with its glued facing is fed through said squeezing rollers it is discharged upon the chute 114.

The throw portion of the cam 101 after 10 the discharge of the book B from the squeezing rollers becomes effective on the roller 100 of the throw arm 97, and causes the rack bar 95 to be effective on the gear 94 in which the upper strand of the link belt 79 is moved forward towards the feed table 1, thereby returning the grippers 69 to a receiving position adjacent said feed table, and as said grippers near the end of their forward travel, the rocking pin 80 of said grippers is engaged by the projection 84 which extends from the end member 2, thereby hinging the upper jaws 72 downwardly on the binding material 7, and prior to the return of said grippers, the cam 14 becomes 25 active towards elevating the operating arm 12, thereby elevating the knife 10 from out of the path of travel of the grippers, and incidental with the reversed travel of the sprocket chain 79, the sprocket 88 will return the weight 91 to an elevated position.

From an inspection of Fig. 7 it is to be noted that the upper jaw 72 of the grippers 69 is provided with an adjustable packing strip 115, said strip being held to the under- 35 side of said upper jaw by the screws 116, and adapted to bear against said strip is a pair of set screws 117. This is for the purpose of providing an even gripping surface relative to both of the grippers, as the binding material which the grippers are adapted 40 to engage and pull is relatively thin, so that any warping whatsoever between either one of the grippers can be neutralized, as it is essential that each of the grippers be provided with an equal amount of plying grip, as the material must be fed onto the guideways flat and straight.

What I claim is:—

1. In a book facing machine, the combination of a book feeding element, means arranged parallel to said element for feeding a strip of glued material to a position lengthwise of said element so that the material will be engaged by the hinging portion of a book at its approximate longitudinal center, and a combined feeding and pressing means arranged parallel to said feeding means for bearing against the side walls of the book and the glued material engaged 55 thereof.

2. In a book facing machine, the combination of a book feeding element, means for feeding a strip of glued material to a position beneath said element and in the path 60 of travel of a book so that said strip will be

engaged by said book when fed by said element, and a rolling device arranged parallel to said feeding means for operating on the walls of the book and the glued strip carried thereby.

70

3. In a book facing machine, the combination of a book receiving and feeding element, a squeezing device, a pair of spaced apart parallelly arranged members located between said feeding element and said device, means for feeding a strip of glued binding material onto said spaced apart members, said feeding element adapted to feed a book against said glued strip and between said spaced apart members and to 80 said squeezing device.

75

4. In a book facing machine, the combination of a book receiving and feeding element, a squeezing device, a pair of spaced apart parallelly arranged members located between said feeding element and said device, a gripping element adapted to reciprocate along said members for feeding a strip of glued binding material onto said members, said feeding element adapted to feed a book against said glued strip and between 85 said spaced apart members and to said squeezing device.

85

5. In a book facing machine, the combination of a book receiving and feeding element, means for discharging books singly to said element, a squeezing device, a pair of spaced apart parallelly arranged members located between said feeding element and said device, means for feeding a strip of glued binding material onto said spaced apart members, said feeding element adapted to feed a book against said glued strip and between 90 said spaced apart members and to said squeezing device.

95

6. In a book facing machine, the combination of a book feeding element, comprised of a pair of parallelly arranged rollers, a pair of squeezing rollers paralleling said other rollers and arranged there beneath, means for feeding a strip of glued material to a position between said feeding element and said squeezing rollers, said feeding element adapted to feed a book against said strip of material and feed said book and said strip to said squeezing rollers.

100

7. In a book facing machine, the combination of a pair of parallelly arranged feed rollers, a book holding magazine, means for discharging books singly from said magazine to said rollers, a pair of squeezing rollers paralleling said other rolls and arranged there beneath, means for feeding a strip of glued material to a position between said feed rollers and said squeezing rollers, said feed rollers adapted to feed a book against said strip of material and feed said book and said strip to said squeezing rollers.

110

8. In combination, a feed table for the reception of a binding material which is pro-

115

120

125

130

vided with an adhesive substance on one side thereof, a pair of feed rollers, a magazine for holding books arranged adjacent said rollers, means for discharging each book singly from the magazine to said rollers, a pair of spaced apart guiding members arranged beneath said rollers, means for drawing the binding material from said table to a position beneath said rollers, means for

severing said material, and a second pair of 10 rollers arranged beneath said members.

9. A gripping device comprised of two jaws, one of said jaws being swingable and having a packing strip secured longitudinally thereto, and means carried thereby for 15 adjusting a portion of said strip.

THOMAS E. HEETER.
